UNITED STATES PATENT OFFICE.

GILES S. MOORE AND OTTO MOORE, OF FRANKFORT, INDIANA; SAID GILES S. MOORE
ASSIGNOR OF HIS ENTIRE RIGHT TO AUTOMATIC SLIDING TROLLEY COMPANY,
OF FRANKFORT, INDIANA, A CORPORATION.

SLEET CUTTER.

1,418,389.

Specification of Letters Patent. Patented June 6, 1922.

Application filed July 27, 1921. Serial No. 487,948.

To all whom it may concern:

Be it known that we, GILES S. MOORE and OTTO MOORE, citizens of the United States, residing at Frankfort, in the county of Clinton, State of Indiana, have invented a new and useful Sleet Cutter, of which the following is a specification.

It is the object of this invention to provide a simple means whereby sleet and ice may be stripped off a trolley wire, without effecting any alterations in the standard trolley harp equipment.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in vertical longitudinal section, a device constructed in accordance with the invention, parts appearing in elevation; Figure 2 is an elevation showing one side of the device; Figure 3 is an elevation showing the opposite side of the device; Figure 4 is a diagrammatic view alluded to in connection with the operation of the structure; Figure 5 is a perspective view showing the frame.

The numeral 1 denotes, generally, a trolley harp, including a socket 2 having an eye 3 for the reception of the trolley rope. Arms 4 project from the socket 2 and are connected at their under edges by a cross bar 5. A shaft or support 6 is carried by the arms 4 and is held in place by cotter pins 7 or otherwise. The ordinary trolley wheel (not shown) or any form of trolley wheel, may be journaled on the shaft or support 6, when the frame 8 (hereinafter described), and parts carried thereby, are removed.

The numeral 8 denotes, generally, a frame, comprising parallel arms 9 having outstanding ears 10 provided with notches or seats 11. The ears 10 are connected by an inner cross piece 12. The arms 9 are supplied with

openings 14. The arms, further, are connected by an outer cross piece 15. The arms 9 carry projecting guards 16 having convexed outer edges 17. Knuckles 18 project from the cross piece 15 and between them is received the knuckle 19 of a pawl 22 carried by a support or pin 20, mounted in the knuckles 18—19 and held in place by cotter pins 21, or in any other suitable way. At its inner end, the part 22 carries a weight 23 tending to swing the outer end of the pawl outwardly.

A shaft 29 is mounted in openings 50 in the outer ends of the arms 9 and is held therein by cotter pins 30 or the like. A wheel 25 is journaled for rotation on the shaft 29 and is located between the arms 9. The wheel 25 includes side plates 26 connected by transverse ribs 27 which are so shaped as to define stripping edges 28. The side plates 26 of the wheel 25 are supplied with peripheral teeth 31, wherewith the outer end of the pawl 22 coacts.

The arms 9 of the frame 8 are received between the arms 4 of the trolley harp 1, the cross bar 5 of the trolley harp being received in the notches 11 which are formed in the ears 10. The shaft or support 6 passes through the openings 14 of the arms 9 and, thus, the frame 8 is held on the trolley harp 1.

The numeral 35 marks a trolley wire. When the car carrying the harp 1 moves forwardly, the stripping edge 28 of one of the ribs 27 rides along the wire 35 and removes the ice or sleet therefrom, it being observed that the pawl 22 coacts with one of the teeth 31 in such a way that the edge 28 of one rib 27 is made effective to scrape the wire 35. When the car is backed, the wheel 25 will rotate on the shaft 29, and, thus, when the car is advanced, a new edge 28 will be presented for engagement with the wire 35. When one of the edges 28 becomes dulled or worn, the appropriate tooth 31 may be filed off, as shown in dotted line at 32 in Figure 4. Consequently, the pawl 22 no longer will engage with that tooth, and the dulled edge 28 will not be presented to the trolley wire.

Should the wheel 25 jump off the trolley wire 35 and be disposed at one side thereof, the lateral guys which support the wire 35 will engage the convexed edges 17 of the

guards 16 and will be directed onto the periphery of the wheel 25, it thus being practically impossible for the device to tear off the lateral wires, jerk down the supporting poles or do any other like damage which ordinarily results when a trolley jumps from the wire.

What we claim is:—

1. In a device of the class described, a frame; a wheel journaled in the frame and provided with cutting edges; and a pawl carried by the frame, the pawl coacting with the wheel to hold any of said edges in operative position.
2. In a device of the class described, a harp including arms and a cross bar connecting the arms; a support carried by the arms; a frame mounted on the support and provided with seats receiving the cross bar; a wheel journaled on the frame and provided with cutting edges; and a pawl mechanism on the frame and coacting with the wheel to prevent the rotation of the wheel in one direction, and to hold any of the cutting edges in working position.
3. In a device of the class described, a frame; a wheel journaled on the frame for

free rotation in one direction and including side plates and ribs connecting the side plates, the ribs having cutting edges; and means for holding the wheel against rotation in an opposite direction, thereby to dispose any of said cutting edges in working position.

4. In a device of the class described, a harp having arms and a cross bar connecting the arms; a frame having open seats receiving the cross bar, and including arms; a support mounted removably in the arms of the harp and in the arms of the frame; a wheel supported for rotation on the arms of the frame for free rotation in one direction, and provided with cutting edges; and means for holding the wheel against rotation in an opposite direction, thereby to dispose any of said cutting edges in working position.

In testimony that we claim the foregoing as our own, we have hereto affixed our signatures in the presence of two witnesses.

GILES S. MOORE.
OTTO MOORE.
